Attorney

UNITED STATES PATENT OFFICE

HENRY ALBERT HERTNER, OF AMARILLO, TEXAS

RELEASING TRAY FOR ICE CUBES

Application filed November 22, 1932. Serial No. 643,905.

This invention relates to a tray for facilitating the removal of ice cubes from a refrigerator tray, the general object of the invention being to provide a tray having a 5 perforated bottom and of a size to receive in an inverted position, the tray of the refrigerator whereby by pouring water over the refrigerator tray, the ice cubes and the partition will be released from the refrigerator tray and will be supported by the larger tray through the perforations of which the water will drain.

This invention also consists in certain other features of construction and in the 15 combination and arrangement of the several parts to be hereinafter fully described, illustrated in the accompanying drawing and specifically pointed out in the appended claim.

20 In describing the invention in detail, reference will be had to the accompanying drawing wherein like characters denote like or corresponding parts throughout the several views, and in which:

25 Figure 1 is a top plan view showing the invention in use with a refrigerator tray.

Fig. 2 is a longitudinal sectional view through the invention.

Fig. 3 is a fragmentary bottom plan view.

30 As shown in these views, the tray A is formed preferably of a single piece of material with substantially straight side and end walls 1 with their ends connected and with a straight and flat bottom 2 which is 35 provided with perforations 3. Flanges 4 are formed on the upper edge of the tray and a downwardly curved handle 5 is formed at one end thereof. Feet forming 40 projections 6 are located on the under face of the bottom 2 adjacent the corners thereof so as to support the tray in spaced relation from the surface on which it is set.

From the foregoing it will be seen that when it is desired to remove ice cubes from 45 a refrigerator tray such as shown at B in Fig. 1, said tray B is placed in inverted position in the tray A and then water, either hot or cold, is poured over the tray B so that the ice cubes and the partitions of the 50 tray B will be released and will rest upon

the perforated bottom of the tray A. Thus by removing the tray B the ice cubes are accessible. The water used to melt the cubes from the tray B will drain through the 55 perforations 3 in the bottom 2.

While the device is mainly intended for facilitating the removal of ice cubes from a refrigerator tray, it can be also used as a colander in which lettuce, celery, etc., might 60 be washed and drained.

It is thought from the foregoing description that the advantages and novel features of the invention will be readily apparent.

It is to be understood that changes may 65 be made in the construction and in the combination and arrangement of the several parts provided that such changes fall within the scope of the appended claim.

Having thus described my invention, what 70 I claim as new is:—

A device of the class described comprising a tray having a flat perforated bottom for receiving the tray of a refrigerator in inverted position thereon whereby by pouring water over the refrigerator tray the 75 cubes of ice will be released and dropped into the first-mentioned tray and the water will drain through the perforations in the flat bottom, said first mentioned tray having upstanding side and end walls vertically 80 arranged, an outwardly extending horizontally arranged flange connected to the upper edges of said walls, a handle forming extension formed on the central portion of that part of the flange connected with one 85 of the end walls, said extension being of the elongated form and having its outer portions curving downwardly and semi-spherical feet forming members having their flat faces connected to the corner portions of the 90 lower face of the flat bottom, said tray including its bottom, walls, flange and handle extension being formed of a single piece of material with the walls imperforate.

In testimony whereof I affix my signature. 95

HENRY ALBERT HERTNER.
